(57) **CLAIM**

The ornamental design for a dispensing device, as shown and described.

DESCRIPTION

FIG. 1 is a top front right perspective view of a dispensing device showing my new design;

FIG. 2 is front view of the design shown in FIG. 1;

FIG. 3 is a rear of the design shown in FIG. 1;

FIG. 4 is a left side view of the design shown in FIG. 1;

FIG. 5 is a right side view of the design shown in FIG. 1;

FIG. 6 is a top view of the design shown in FIG. 1; and,

FIG. 7 is a bottom view of the design shown in FIG. 1.

The broken lines shown in the figures are included for the purpose of illustrating portions of the dispensing device and form no part of the claimed design.
